His Attorney.

UNITED STATES PATENT OFFICE.

JOHN A. SEEDE, OF SCHENECTADY, NEW YORK, ASSIGNOR TO GENERAL ELECTRIC COMPANY, A CORPORATION OF NEW YORK.

STATIONARY INDUCTION APPARATUS.

1,397,298.

Specification of Letters Patent.

Patented Nov. 15, 1921.

Application filed February 15, 1921. Serial No. 445,112.

To all whom it may concern:

Be it known that I, JOHN A. SEEDE, a citizen of the United States, residing at Schenectady, county of Schenectady, State 5 of New York, have invented certain new and useful Improvements in Stationary Induction Apparatus, of which the following is a specification.

My invention relates to stationary induction apparatus and particularly to transformers provided with taps. It has for its general object an improved arrangement of parts for making the desired tap connections which is rugged, safe and economical; 15 a specific object of my invention being to provide the apparatus with a terminal board for the taps which is arranged in such a manner that the taps will necessarily always be properly connected.

For many kinds of services supplied with alternating current from stationary induction apparatus, it is known to be advantageous to have a definite amount of relatively high reactance in the circuit especially in the stationary induction apparatus itself. This is particularly true of transformers adapted to supply current for welding purposes, especially arc welding. The most expeditious way of constructing the 30 apparatus to have this internal reactance is to place some of the turns of the load circuit in poor inductive relation with those of the primary circuit, the balance of the turns in the load circuit being in good inductive 35 relation with those of the primary.

In such apparatus it is frequently desirable to construct it so that the internal reactance may be varied from time to time to suit the characteristics of the particular load 40 being served. Provision to this end invariably involves the use of taps in the windings of the load circuit so that the number of turns in poor inductive relation and in good inductive relation may be varied. Unless special precautions are taken the provision of a plurality of taps produces confusion and uncertainty on the part of the operator as to whether the proper tap connections have been made.

In the practice of my invention this uncertainty is entirely avoided for I make use of a terminal board to which the taps are led and disposed in such an order that for every turn or turns in good inductive relation cut out, a corresponding number of

turns in poor inductive relation are cut in or vice versa.

For a more complete understanding of the nature and objects of my invention, reference should be had to the following detailed 60 description taken in connection with the accompanying drawing in which:

Figure 1 shows in perspective a transformer, such as used in arc-welding outfits, provided with my invention; while Fig. 2 65 is an explanatory diagram.

Referring now to the drawings, 10 denotes the core of a transformer having windings 11 mounted thereon. The apparatus, for the class of service indicated, is preferably 70 mounted so as to be portable. To this end it is shown as mounted on a truck 12. The high voltage leads are indicated at 13 while 14 denotes the low voltage leads, having attached thereto electrodes 15; one suitable 75 for welding, the other adapted to be secured to the "job."

The tap-leads, which lead from the turns in good and poor inductive relation with the primary, are shown at 20 and extend to the 80 terminal board 21 disposed on the top of the apparatus so as to be readily accessible. These leads are secured to conducting terminals 22, shown on the top of board 21, and are preferably of a form adapted to be engaged by a connecting plug or contact-making device 23, which is manually manipulated, the same being designed to be withdrawn from one pair of terminals and inserted in another. 90

These terminals 22 are disposed in parallel rows along the sides of the terminal board 21, as shown in Fig. 2. All terminals in one row (the top row in Fig. 2) are connected to taps t_1 , t_2 , t_3 , etc., which lead successively to the turns in the portion S of the secondary winding which may be cut out and are in good inductive relation with the primary winding P. 95

In like manner the terminals in the other 100 row (the bottom row in Fig. 2) are connected to the taps u_1 , u_2 , u_3 , etc., which lead successively to the turns in the portion L of the secondary winding which may also be cut out but are in poor inductive relation 105 with the primary winding.

The terminals from the taps are, however, arranged in inverse order, i. e. the tap t_1 leading to the first turn to be cut out in portion S is disposed opposite the terminal for tap 110

u_6 leading to the last turn in portion L which may be cut out. Similarly the terminal for tap t_5 leading to the second turn in portion S which may be cut out is disposed opposite 5 the terminal for tap u_4 leading to the next to the last turn in portion L, which may be cut out; and so on until the terminal for tap t_5 is disposed opposite the terminal for tap u_1 .

By this arrangement, the connection making 10 plug 23 which is adapted to span only one pair of terminals at a time cannot connect together the taps in any combination other than those desired. As shown whenever the plug 23 is moved to cut out one or 15 more turns from the portion of the winding S, a corresponding number of turns in the portion L are cut in and vice versa.

It is thus seen that the terminal voltage 20 across the electrodes 15 is substantially the same for any set of tap connections but the per cent. of internal reactance is changed with each set of tap connections; since the turns in the portion L of the secondary winding are highly reactive being in poor inductive 25 relation with the primary. On the other hand, the turns of the portion S of the secondary have very low reactance since they are in good inductive relation to the primary.

30 Accordingly it is seen that the per cent. reactance is proportional to the ratio of turns in L in series with the load to the turns in S likewise in series with the load. This arrangement has particular advantages in connection with arc-welding where it is frequently desirable to change the per cent. reactance in series with the arc to get the best 35 operating conditions.

Having now described an embodiment of 40 my invention which is at present the best means known to me for carrying the same into effect, I would have it understood that this is merely illustrative, and that I do not mean to be limited thereby to the precise details shown nor restricted in the choice of 45 recognized equivalents except as defined in my claims hereunto annexed.

What I claim as new and desire to secure 50 by Letters Patent of the United States, is,—

50 1. In stationary induction apparatus, the combination with a core, and two windings disposed thereon in mutual inductive relation, a portion of one winding being in good inductive relation with the other winding and another portion in poor inductive relation, of means for simultaneously cutting 55 out turns from one of said portions and cutting in a corresponding number of turns of the other portion, whereby the per cent.

reactance is altered without altering the resultant terminal voltage of said portions. 60

2. In stationary induction apparatus, the combination with a core, and two windings disposed thereon in mutual inductive relation, a portion of one winding being in good 65 inductive relation with the other winding and another portion in poor inductive relation, of taps leading to separate turns on said portions, and means for connecting said taps for cutting out turns from one of said portions and simultaneously cutting in a corresponding 70 number of turns on the other portion, whereby the per cent. internal reactance is altered without altering the resultant terminal voltage of said portions. 75

3. In stationary induction apparatus, the combination with a core, and two windings disposed thereon in mutual inductive relation, a portion of one winding being in good 80 inductive relation with the other winding and another portion in poor inductive relation, of taps leading to separate turns on said portions, and a terminal board for said taps having a coacting contact-making device, the terminals of said taps being relatively 85 disposed on said board so as to yield a desired terminal voltage across said portion for 90 every position of said device, each different position altering the number of active turns in circuit in one of said portions and simultaneously altering the number of turns in circuit in the other portion in inverse ratio, whereby the total number of turns in said portions in circuit for any position of said contact device is always the same. 95

4. In stationary induction apparatus, the combination with a core, and two windings disposed thereon in mutual inductive relation, a portion of one winding being in good 100 inductive relation with the other winding and another portion in poor inductive relation, of taps leading to separate turns on said portions, and a terminal board for said taps having a contact-making device for its terminals, said terminals being disposed 105 relatively in parallel rows, the tap to the first turn of one of said portions being opposite the tap to the last turn of the other portion, the inverse order being continued successively for all the tap terminals of the turns in 110 the said portions, whereby the contact device may be moved to alter the number of active turns in circuit in the respective portions but without altering the total active turns.

In witness whereof, I have hereunto set my 115 hand this 12th day of February, 1921.

JOHN A. SEEDE.
